UNITED STATES PATENT OFFICE.

THOMAS D. MILLEA, OF SPRINGFIELD, MASSACHUSETTS, ASSIGNOR TO SPRINGFIELD ENGINE STOP COMPANY, OF NEW YORK, N. Y., A CORPORATION OF MAINE.

STOP MECHANISM FOR ENGINES.

SPECIFICATION forming part of Letters Patent No. 694,877, dated March 4, 1902.

Application filed May 9, 1896. Serial No. 590,833. (No model.)

To all whom it may concern:

Be it known that I, THOMAS D. MILLEA, a citizen of the United States of America, residing in Springfield, in the county of Hampden and State of Massachusetts, have invented new and useful Improvements in Stop Mechanisms for Engines, &c., of which the following is a specification, reference being had to the accompanying drawings and letters of reference marked thereon.

The object of my invention is to provide a stop mechanism which shall be simple and effective and by which the source of power employed for driving the engine or motor may be also employed for the purpose of stopping it.

My object is, further, to provide a device having sufficient power to insure effective action and at the same time easy to put in operation, and to provide a device which may operate directly upon the governor, the shut-off valve, or the reach-rods, and a device adapted to break off vacuum in a condensing engine at the same time the live steam is shut off, if desired.

I attain the objects of my invention by the construction herein set out.

In the accompanying drawings, in which like letters of reference indicate like parts, Figure 1 is a perspective view of a portion of an ordinary ball-governor, having arranged adjacent thereto a cylinder and piston adapted to operate to cause the governor to move in a direction to shut off the supply to the main cylinders of the engine. Fig. 2 is a perspective of an electromagnetic device adapted to admit steam to the governor-cylinder whenever the magnets are energized. Fig. 3 is a side elevation of the same on an enlarged scale. Fig. 4 is a view in vertical section, illustrating the construction in detail of a portion of the valve illustrated in Fig. 3. Fig. 5 is a side elevation showing the arrangement of two valves mounted adjacent to each other, one being adapted for the admission of steam to the governor-cylinder and one for the admission of air to the vacuum-chamber or vacuum end of a steam-cylinder. Fig. 6 is a top view of two valves mounted adjacent to each other and with a single lever adapted

to control both. Fig. 7 is a side elevation illustrating the application of my invention, wherein a cylinder is employed not only for the purpose of operating the governor, and thus shutting off the source of power, but also another like cylinder, but preferably of less size, employed to destroy the vacuum. Fig. 8 illustrates the application of the same method of operation directly to the reach-rods of the "Corliss" type of engine. Fig. 9 illustrates a mechanical construction for tripping the lever and opening the valve, which may be used independently of or in conjunction with the electric mechanism; and Fig. 10 is a vertical section of a valve wherein a spring is employed to open the valve against pressure and preferably employed for destroying the vacuum.

In detail, A indicates a ball-governor banjo or staff; B, governor-cylinder; C, support for electromagnets, armature, and lever; D and E, valves; F, electromagnets; G, armature; H, lever; I, valve-stem cap; J, K, L, and M, conduits; N, governor-stem; O, rocker; P, governor-cylinder inlet; R, branch conduit; S, valve-lever.

a indicates the piston-rod of the governor-cylinder; b, a rod projecting from the governor-stem into the path of the governor-cylinder piston-rod; c, a supporting-bracket mounted upon the banjo; d, a bracket mounted upon the bracket c; e, insulating material between the two brackets; f, a tubular support mounted in bracket d; g, a rod adjustably mounted in the part f; h and h', adjustable collars; i and i', contact points or springs; j, a bracket mounted upon plate C, adapted to support the armature; k, an extension or arm for the armature; l, armature retractile spring; m, valve-seat; n, valve-stem; o, valve-disk; p, seating-spring; q, pin or screw; r, lever-valve stem; s, rocker-arm lever; t, arm-on governor-stem; u, rocker; v, lever; w, connecting-rod; x, armature-actuating lever; y and z, valve-stem sprigs.

The construction and operation of my device will be readily understood on reference to the drawings, in which in Fig. 1 I illustrate one of the simplest forms of arranging my device, taking for the purpose of illustra-

tion an ordinary ball-governor. I mount upon the banjo or staff or adjacent thereto a bracket *c*, upon which is supported a cylinder *B*, it being provided with a piston and piston-rod of any convenient form of construction, and an arm *b* is mounted in the governor-stem, which arm projects into the path of the piston-rod *a*. It will now be seen that if steam be allowed to enter the cylinder the piston 5 will be forced upwardly and the end of the piston-rod brought in contact with the arm *b*, thus forcing the stem upwardly and operating through intermediate mechanism to close the supply of steam to the engine-cylinders, 10 and thereby cause the stopping of the engine. 15 In order to bring the governor-cylinder mechanism into operation, I illustrate in Figs. 2 and 3 a convenient valve and let-off mechanism, consisting, preferably, of two electromagnets *F*, mounted upon a plate *C*, and pivotally mounted adjacent to the cores of the magnets is the armature *G*, provided at its lower end with an extension *k* and a retractile spring *l*. The valve preferably consists 20 of a valve-body, such as shown in Fig. 3, having an interior seat *m*, as shown in Fig. 4, and a stem *n*, provided at its end with a valve-disk *o*, the end of which stem projects through suitable packing, and over the end portion of 25 the stem is arranged a cap *I*, and between the stem end and bottom of the recess in the cap is arranged a spring *p*. The object of this spring is to avoid the nice adjustment which would otherwise be required to seat the valve-disk and maintain it in accurate closed position 30 against pressure by the operation of a lever fixed in position. This spring, therefore, will compensate for all slight variations and enable me to maintain the valve closed against 35 pressure regardless of the exact position of the lever.

The lever *H* is pivotally mounted upon the plate *C*, and its short arm bears against the top of the cap *I*, while its opposite end bears 45 upon the armature *G* when the magnets are not energized. When, however, the magnets are energized, the armature is drawn toward the magnets and out of the path of the lever *H*, thus allowing it to turn upon its pivot and 50 fall by gravity to the position indicated in dotted lines in Fig. 3, and at the same time the pressure upon the cap is removed, so that the valve-disk may be raised from its seat by the steam-pressure and steam permitted to 55 pass through the valve into the conduit *J* and thence to the conduit *P* and enter the governor-cylinder *B*, thus causing the govnor to operate, as before stated, and shut off the supply of steam to the engine-cylinder. To prevent 60 the accidental removal of the cap *I* from the valve-stem *n*, the stem is slotted, and a screw or pin *q* passes through the cap and slot.

The conduit *K* is connected directly with the steam-space on the boiler, so that it will 65 be observed the steam-pressure which operates to drive the engine is also utilized to stop it when desired.

The electromagnets are of course electrically connected with switches or push-buttons at various convenient points in the different rooms of a factory or other building, so that in the event of an accident the engine may be immediately stopped by moving the switch or pressing the button, thus energizing the magnets and causing the device to 70 operate, as before stated. 75

For the purpose of a speed-limit attachment to cause the device to operate in the event of the governor-belt slipping or if for any cause the engine should attain a higher 80 rate of speed than desired, in which event it becomes desirable to automatically shut down the engine, I provide contact-pins *i* and *i'*, mounted adjustably upon an adjustable rod *g*, which rod is mounted, preferably, in a tubular support *f*, the latter being mounted in a bracket *d*, electrically insulated from the bracket *c*. If now the governor-belt should break, the arm *b* would be carried downwardly because of the balls falling to 85 their lowest limit and the arm *b* would be brought in wiping contact with the contact-piece *i*, thus making electrical connection between the governor-stem and the electromagnets, thus causing the magnets to be energized, the armature to be operated upon, the valve opened, and the steam shut off, while, on the other hand, if the engine should attain a higher rate of speed than desired the arm *b* would be carried upwardly until it came in 90 contact with the contact-piece *i'*, thus making the same electrical connection before 95 described when operating to stop the engine. 100

With condensing-engines it has been found that notwithstanding the fact that steam is 105 shut off the engine would continue to run until the vacuum was destroyed, and for the purpose of overcoming this objectionable feature I provide a means for admitting air either 110 into the vacuum-chamber or directly to the valve mechanism connecting with the cylinders, and it will be seen that the same arrangement of electromagnets, lever, and valve may be employed for that purpose, and in 115 Fig. 5 I have shown two valves arranged adjacent to each other, one being adapted for the admission of steam to the governor-cylinder and the other for the admission of air to the vacuum-chamber or other desired point. If, however, it is desired, the lever may be arranged to operate upon both valves, so that 120 but one arrangement of electromagnets, lever, and support would be required, and in Fig. 6 I show in plan view a portion of a lever provided at the end with an enlargement or 125 T-head arranged to engage both the steam-valve and the vacuum-valve, so that, as before stated, both will operate by the same electric device.

In Fig. 7 I illustrate an arrangement of 130 parts wherein a cylinder is employed to operate each valve, the two cylinders *B* and *B'* being connected with the same steam-valve *D* by means of branch conduit *R*, conducting

the steam to the cylinder B', the piston-rod of which cylinder engages a weighted lever S, which in turn raises the valve-stem r, and thus the valve-disk o, and allows the air to rush in through suitable conduits and destroy the vacuum, so that the operation of the device will shut off the supply of steam, as before stated, and destroy the vacuum, thus causing an immediate stoppage.

10 Fig. 8 shows a method whereby the operation described in connection with Fig. 1 is reversed by means of the cylinder B and the piston-rod a, the lever s being forced upward and the connecting-rod between the governor and the lever opposite the piston being forced downward, thereby bringing the governor to its lowest position and preventing the hooks from opening the side valves.

In Fig. 9 I illustrate a construction wherein the armature will be mechanically moved toward the magnets and out of the path of the lever H, it consisting in providing the governor-stem N with a projecting piece t, which engages a rocker-arm u, causing it to be turned from its normal position by the upward or downward movement of the stem N and causing the rocker in either event to engage a pivoted lever v, which in turn operates through the medium of the connecting-rod w upon a lever x, forcing the free end of the latter against the armature, forcing it toward the magnets and out of the path of the lever H, as before explained, thus putting in operation the shut-off mechanism.

35 In some instances a vacuum-valve provided with a straight stem and spring will be more convenient than the lever-valve before described, and for the purpose I provide a valve construction as illustrated in Fig. 10, the valve-body cap and seating-spring being substantially the same in construction as described with reference to Figs. 2 and 3. With this valve, however, the stem is extended upwardly a sufficient distance to enable me to interpose two springs y and z, the latter having sufficient tension to overcome the atmospheric pressure, so that upon the lever H being turned to permit the stem to move upwardly the spring z will operate against the collar fastened to the stem and lift the valve-disk against atmospheric pressure. In order, however, to maintain the valve-disk in its closed position, it becomes necessary to provide a spring above the spring z having sufficient tension to overcome the tension of the spring z and something in addition. For the purpose of illustration suppose the spring z have a tension sufficient to develop a power when springing open of seventeen pounds to the 50 square inch and that the spring y have sufficient tension when compressed or forced downwardly to develop a power or pressure equal to eighteen pounds per square inch. The valve-disk will be held upon its seat with the pressure of one pound per square inch, and when the pressure upon the spring y is released the spring z is free to operate to lift

the stem and disk, and thus permit the passage of air, as before described.

The governor mechanism acting directly upon the valves which control the supply of steam to the engine may be styled the "main" shut-off mechanism, and the devices which act upon this main shut-off mechanism—as the cylinder B with its piston-rod, the valve 75 in the conduit J, and the electrical apparatus for actuating said valve—may be termed the "auxiliary" shut-off mechanism, since these latter devices or members taken together are accessory to the governor mechanism and in reality compose a secondary or auxiliary mechanism for indirectly operating or shutting off the engine-valves.

It will readily be seen that very many modifications in detail of construction may be employed without departing from my invention. 85 It will also be seen that without material alterations the device may be made operative by the employment of a closed circuit as well as with an open circuit, as herein described.

Having therefore described my invention, what I claim, and desire to secure by Letters Patent, is—

1. The combination, with a motor having a main shut-off mechanism, of a shut-off cylinder provided with a piston and piston-rod independent of the main shut-off mechanism, a conduit extending from the shut-off cylinder, to the source of power, a valve in said conduit, a lever arranged to control said valve, an armature adapted to maintain said lever in a fixed position, an electromagnet arranged to move the armature and thereby release the lever, said electromagnet being connected by suitable conductors with a source of electrical energy, and means interposed in the path of the piston-rod of the shut-off cylinder to cause the operation of the main shut-off mechanism which in turn operates to shut off 100 the motive force to the motor, substantially as set forth.

2. In combination with a motor and main shut-off mechanism therefor, an auxiliary shut-off mechanism consisting essentially of 115 a shut-off cylinder having a piston and piston-rod arranged to operate the main shut-off mechanism to cut off the supply of steam or other motive force to the motor, the shut-off cylinder, piston and rod being independent 120 of the main shut-off mechanism, a conduit extending from the shut-off cylinder to the boiler or other reservoir of power, a valve in said conduit, a lever adapted to control said valve, an armature adapted to hold said lever in its normal position, and an electromagnet capable when energized of moving said armature to set free the lever, substantially 125 as set forth.

3. In combination with a motor and a main 130 shut-off mechanism therefor including a governor, an auxiliary shut-off mechanism independent of the main shut-off mechanism, consisting essentially of a cylinder provided with

- a piston and piston-rod, a conduit extending from the shut-off cylinder to a reservoir of motive force, a valve in said conduit, a lever arranged to control said valve, an armature adapted to hold said lever in normal position, an electromagnet to operate the armature and thereby set free the lever and open the valve, a projection having its position controlled by the governor, and an adjustable contact-point in the path of said projection, the projection, contact-point and electromagnet being in the same electric circuit when the two former are in contact, substantially as set forth.
- 15 4. In a shut-off mechanism operated by steam or fluid pressure, a lever, an inlet-valve maintained in its normal closed position by said lever and a spring-provided part interposed between the holding-lever and stem, the lever being free when released to move out of the path of the stem and release the pressure upon the spring and leave the valve free to open, substantially as shown.
- 25 5. In a shut-off mechanism operated by steam or fluid pressure, an inlet-valve having a stem-provided valve-disk, a cap arranged upon the stem, a spring interposed between the two, and means to hold the cap in position to compress the spring, substantially as and for the purposes shown.
- 35 6. In combination with a low-pressure motor, a shut-off cylinder provided with a piston-rod arranged to shut off the supply of steam or other motive force to the engine-cylinder, a conduit leading to the shut-off cylinder for the conveyance of motive force thereto, a valve arranged therein, a conduit leading to the vacuum, a valve arranged in said conduit, and means to open both said valves at substantially the same time, substantially as and for the purposes shown.
- 45 7. In combination with a low-pressure motor, two valves arranged adjacent to each other, one being connected with a shut-off mechanism to shut off the supply of steam or other motive force and the other connected with the vacuum, and a pivotally-mounted lever operatively controlling both said valves, and means to control said lever, substantially as shown.

8. In a stop mechanism, the combination of a governor, a projection the position of which is governed by the speed of the motor, one or more contact-pieces adjustably arranged in the path of said projection, and a shut-off device adapted to be put in operation by an electric device, said electric device and contact-pieces being in electrical connection only when one of said pieces is in contact with said projection, substantially as set forth. 60

9. The combination, of a governor, a projection on one of the movable parts thereof, a shut-off cylinder having a piston and piston-rod the latter being arranged to engage said projection, when operated, contact-pieces 65 suitably mounted in the path of the projection, a conduit leading to the shut-off cylinder, a valve in said conduit, an electrically-operated valve-operating device, a source of electrical energy, and suitable electric conductors employed to bring the contact-pieces into circuit when in contact with the projection, substantially as set forth.

10. The combination, in a shut-off mechanism, of an inlet-valve, a spring to hold said valve closed when said spring is under tension, a conduit extending from the valve to the source of power, a cylinder provided with a piston and piston-rod adapted to operate to close the main shut-off valve of a motor, a 75 conduit extending from said inlet-valve to said cylinder, a lever arranged to maintain said spring under tension, an armature to engage one end of said lever, an electromagnet to move said armature, when energized, and means to energize said electromagnet at will, substantially as set forth.

11. In a shut-off mechanism for a vacuum-engine the combination of a cylinder, a piston and piston-rod arranged to shut off the supply of steam to the engine-cylinder, a conduit leading to the shut-off cylinder, a valve arranged therein, a conduit leading to the vacuum, a valve arranged therein and means to open both said valves by the operation of a single releasing device, substantially as shown. 90
